UNITED STATES PATENT OFFICE.

SAMUEL SWARTCHILD, OF CHICAGO, ILLINOIS.

DESIGN FOR A JEWELER'S CABINET.

SPECIFICATION forming part of Design No. 35,467, dated December 24, 1901.

Application filed November 7, 1901. Serial No. 81,506. Term of patent 3½ years.

To all whom it may concern:

Be it known that I, SAMUEL SWARTCHILD, a citizen of the United States, residing at Chicago, in the county of Cook and State of Illinois, have invented and produced a certain new and original Design for Jewelers' Cabinets, (Case No. 1,) of which the following is a full, clear, concise, and exact description, reference being had to the accompanying drawing, forming a part of this specification.

My invention relates to a design for jewelers' cabinets, and is illustrated in the accompanying drawing, showing a perspective view of the cabinet.

15 The leading or material feature of my design consists in a series of bars *a a*, extending horizontally across and located within the cabinet; boards *b b* upon the interior of the casing, having oblique pockets *c c*, into which 20 the bars or rods *a* project; hooks *d d*, depending from the rods; a door *e*, provided with a glass panel *f*, and a frame *g* at the rear of the cabinet, supporting a back *h*, affording a reflecting-surface.

The cabinet is provided with a decorative 25 base *i* and a decorative top, having an upper flaring portion *k* and decorative moldings *l l*.

The cabinet has rectangular sides, back, and front, excepting for the decorative moldings *i*, *k*, and *l*. Its base and top are also rectangular.

The sides of the cabinet are several times as high as the cabinet is deep.

The front and back of the cabinet are only slightly higher than the cabinet is wide. 35

Having described my invention, what I claim as new, and desire to secure by Letters Patent, is—

30 The design for a jewelers' cabinet, as herein shown and described.

In witness whereof I hereunto subscribe my name this 28th day of October, A. D. 1901.

SAMUEL SWARTCHILD.
